CLAIM

The ornamental design for an expansion chamber, as
shown and described.

DESCRIPTION

FIG. 1 is a perspective view of an expansion chamber
showing my new design;

FIG. 2 is a plan view of one side thereof, the other side
being substantially a mirror image;

FIG. 3 is a side elevational view thereof; and
FIG. 4 is an end elevational view thereof.

FIG. 1

FIG. 4

FIG. 2

FIG. 3
